CLAIM

The ornamental design for a base configured to support an optical scanner as shown and described.

DESCRIPTION

FIG. 1 is a top, front left perspective view of a base configured to support an optical scanner showing our new design;

FIG. 2 is a top, front right perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The dash-dot-dash broken lines adjacent shaded areas represent bounds of the claimed design and form no part of the claimed design. All other broken lines depict unclaimed features and form no part of the claimed design.
